CLAIM

The ornamental design for a blow dryer, as shown and described.

DESCRIPTION

FIG. 1 is a front, right perspective view of a blow dryer showing the new design;

FIG. 2 is a rear, left perspective view thereof;

FIG. 3 is a right-side elevation view thereof;

FIG. 4 is a left-side elevation view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a front, right perspective view thereof in a bent configuration; and,

FIG. 10 is a rear, left perspective view thereof in a bent configuration.

(Continued)

The broken lines illustrate portions of the blow dryer and form no part of the claimed subject matter.

1 Claim, 8 Drawing Sheets
